UNITED STATES PATENT OFFICE.

HARRISON J. FLEGEL AND JOHN HUBENTHAL, OF RACINE, WISCONSIN.

ANTI-RAIL-CREEPER.

1,195,669.

Specification of Letters Patent. Patented Aug. 22, 1916.

Application filed May 13, 1916. Serial No. 97,243.

To all whom it may concern:

Be it known that we, HARRISON D. FLEGEL and JOHN HUBENTHAL, both citizens of the United States, and residents of Racine, in the county of Racine and State of Wisconsin, have invented certain new and useful Improvements in Anti-Rail-Creepers; and we do hereby declare that the following is a full, clear, and exact description thereof.

10 Our invention has for its primary object to provide an anti-creeper attachment for railway rails, wherein a rail tie-plate is arranged to co-act with rail gripping clips to cause said clips to frictionally bite the rail with increasing force, in proportion to the tendency of the rail to creep. Thus a metallic contact between the stationary element and the movable element is attained to produce a positive gripping result to hold 15 the rail, in contradistinction to the ordinary method wherein the rail-gripping member is opposed by the standard wood tie.

Another object of our invention is to provide an anti-rail-creeper which will act with 20 equal efficiency to prevent creeping of the rail in either direction.

It is also within the scope of our invention to provide a simplified form of the anti-creeper containing the generic principles set 25 forth, but capable of operating in connection with a rail wherein traffic in one way only is the mechanical problem offered.

It is also an object of our invention to provide an exceedingly simple anti-rail-creeper embodying a fixed metallic element and a rail-carrying metallic element, which elements operate frictionally, due to the 30 tendency of the rail to creep, without the assistance of springs or other members to 35 become damaged or broken.

With the above and other minor objects in view the invention consists in certain peculiarities of construction and combination of parts as hereinafter set forth with reference to the accompanying illustrations and 40 subsequently claimed.

In the drawings Figure 1 represents an inverted plan view of an anti-rail-creeper embodying the essential elements of our invention; Fig. 2, a longitudinal sectional view through the same, the section being indicated by line 2-2 of Fig. 1; Fig. 3, a cross-section through the rail and its gripping clips, the section being indicated by 45 line 3-3 of Fig. 1, and Fig. 4, a detailed face view of one of the rail clips showing

the method of locking the clamping nut, which clip is opposed by the thrust-arm of the pad-plate.

Referring by characters to the drawings, 50 1 represents a tie-plate which is secured to the wood tie by spikes 1', the said spikes also serving to clamp the base flange 2 of the rail in place in the usual manner. The tie-plate in this exemplification of our invention is provided with a longitudinally extended thrust-arm 3 and a pull-arm 3', the pull-arm being provided with a down-turned jaw 4.

Secured to the base flange 2 of the rail 50 are a pair of gripping clips 5, 5', each of which is provided with channels 6, into which the edges of the rail base flange are fitted. The clips are firmly locked in their positions upon the base flange by a bolt 7, 55 which bolt passes through suitable apertures that are formed in the clips aforesaid. The head 7' of the bolt is fitted in a rectangular seat 8 that is formed in the clip 5', whereby said bolt is held against twisting under the 60 vibratory strain imparted thereto due to traffic over the rail. The opposite clip 5 is also provided with a rectangular seat 8' about the bolt aperture for the reception of a boss 9 that forms part of a washer 10, 65 the said boss being rectangular in shape so as to prevent rotary movement of the washer. The flanged portion of the washer which abuts the juxtaposed face of the clip 70 is provided with a series of companion radially disposed cuts at its periphery, whereby a series of locking tongues 11 are formed, as shown. After the nut 7" of the clamping bolt is firmly seated to draw the clips into the proper engagement with the base flange 95 of the rail, it is desirable to prevent any tendency of the nut to work loose. Hence one or a plurality of the locking tongues 100 may be bent down as shown and firmly pressed against the faces of the nut to thus hold the same against movement with relation to the washer, which washer, as previously stated, is locked in its seat 8' formed in the clip.

Hence it will be seen that the parts can 105 very quickly and readily be assembled by those not necessarily skilled in the art and the bolt and nut will serve to draw the clips as firmly as possible to the edges of the rail base flange and in this initial assemblage, 110 as shown, the bolt extends approximately at a right angle to the longitudinal axis of the

rail and it follows that the channels 6 are gripped to the edges of the rail in parallel relation thereto. In this initial assembled position of the parts, the clip 5 will abut the 5 end face of the thrust-arm 3 and the jaw 4 of the pull-arm 3', as shown in Fig. 2, will be in approximate contact with an upturned jaw 12 of a finger 13, which finger projects from the clip 5'. In this initial position 10 of the parts, should the rail tend to creep in the direction as indicated by the uppermost arrow in Fig. 1, the thrust-arm 3 will prevent movement of the clip 5, while the clip 5' will advance with the creeping rail 15 in the direction of the uppermost arrow. Thus it will be seen that the bolt will take a slightly oblique position, as will also the gripping clips, whereby said gripping clips by their skew will cause an abnormal gripping 20 engagement of their channeled surfaces with relation to the rail and thereby lock the rail against creeping. Should the rail tend to creep in the opposite direction, as indicated by the lower arrow, the end of 25 the thrust-arm 3 will travel slightly away from its contact with the clip 5 and the jaws 4 and 12 of the pull-arm 3' and finger 13 respectively will be brought into locked engagement, whereby the creeping tendency 30 of the rail will exert a friction grip of the clips in the same manner as that previously described. Thus it will be seen that by the arm elements associated with the tie plate, a metallic contact is effected between the 35 clips, whereby an abnormal gripping strain is put upon them irrespective of the direction of travel of the rail due to its tendency of creep. Hence the device will operate efficiently for single tracks where the traffic is 40 moved in both directions.

It is manifest that for double tracks or in instances where the traffic is in one direction only, a single arm may be employed in connection with a tie-plate to co-act with a clip- 45 member to obtain the desired results.

It will also be observed that primarily the anti-rail-creeper as a whole comprises only four parts, to wit: the tie-plate, two clip-plates, and the bolt element,—and that no 50 springs or mechanism to become loose or jarred is embodied in the structure. In other words, the greater the tendency of the rail to creep, the greater the friction force will be applied to the clips to prevent such

creeping and if any wear takes place this 55 friction force is sufficient to automatically take up such wear.

We claim:

1. An anti-creeper for rails comprising a tie-plate having a thrust-arm and a pull- 60 arm extending therefrom beyond the body of the tie to which the tie-plate is secured, a pair of channel gripping clips adapted to be fitted to the edges of the rail, a tie-bolt for the gripping clips, means for effecting abut- 65 ting engagement with one of the clips and the thrust-arm, and means for effecting a pulling engagement between the other clip and said pull-arm, whereby the aforesaid 70 clips are caused to exert an abnormal frictional gripping engagement or draw upon the rail flange irrespective of the direction of movement of said rail.

2. An anti-creeper for rails comprising a tie-plate having a thrust-arm and a pull- 75 arm extending therefrom beyond the body of the tie to which the tie-plate is secured, a pair of channel gripping clips adapted to be fitted to the edges of the rail, a tie-bolt for the gripping clips, means for effecting abut- 80 ting engagement with one of the clips and the thrust-arm, and jaws for interlocking engagement between the pull-arm and other clip, whereby the aforesaid clips are caused to exert an abnormal frictional gripping en- 85 gagement or draw upon the rail flange irrespective of the direction of movement of said rail.

3. An anti-creeper for railway rails comprising a tie-plate for supporting the rails 90 adapted to be secured to a tie, an arm extending from the tie-plate beyond the tie body, channeled clips fitted to the base flange of the rail, the face of one of which clips is in juxtaposition to the arm whereby it will 95 abut the same when the rail creeps in one direction, and a clamping bolt connecting the clips crosswise of said rail base flange.

In testimony that we claim the foregoing we have hereunto set our hands at Racine, 100 in the county of Racine and State of Wisconsin, in the presence of two witnesses.

HARRISON D. FLEGEL.
JOHN HUBENTHAL.
